Inventor.
W. L. Woods.

UNITED STATES PATENT OFFICE.

W. L. WOODS, OF WASHINGTON, DISTRICT OF COLUMBIA, ASSIGNOR TO
HARRIET WOODS, OF CENTREVILLE, INDIANA.

PAPER-FILE.

Specification forming part of Letters Patent No. 36,200, dated August 12, 1862.

To all whom it may concern:

Be it known that I, W. L. Woods, of Washington city, in the District of Columbia, have invented a new and Improved Paper-File and Document-Safe, the use of which is to facilitate the handling of business papers and for their preservation; and I do hereby declare that the following is a full, clear, and exact description of the construction and operation of the same, reference being had to the annexed drawings, making a part of this specification.

The nature of my invention consists in the construction of a folding box so arranged that the inside will slip out in part, so as to enable the operator to examine the papers on file by their titles without removing them from the safe, and close up in a compact manner, the whole combination forming a practical paper-file and document-safe suitable for all ordinary business departments, and preserving the papers from the dust and the usual wear of handling.

To enable others skilled in the art to make and use my invention, I will proceed to describe its construction and operation.

I construct my paper-file and document-safe of any suitable size and out of any suitable materials used by carpenters, book-binders, box-makers, tin and copper smiths, and in the form of a folding box, as shown open and closed by Figures 1, 2, and 3 in the annexed drawings, which folding box is composed of an exterior box, (see *a*, *b*, *c*, *d*, *e*, and *f*, Fig. 2, and *a*, *d*, *e*, and *f*, Fig. 3,) with a raising cap-lid, *g h i*, Fig. 2, and *i g*, Fig. 3, which closes against diagonal shoulders *f x*, or may be let over the sides of the box without shoulders, and which lid is fastened to the front end of the box by a hinge, *C C*, Fig. 1, which top is about three-fourths the length of the box, and an interior box, (shown by dotted red lines and broad black lines, indicated by *strqvnk*,) which inner box is not separate from nor cannot be separated from the exterior box, but only drawn out in part, the front edge of the top *v*, Fig. 2, coming in contact with the cleat *x*, which is placed immediately under the hinge

of the cap-lid and extending across on the under side of the top of the exterior box. This cleat is of the same thickness as the top of the interior box. The sides of the interior box are equal, and are cut diagonally from the front edge of the top to the front edge of the bottom, where the falling lid *l m n k*, Fig. 2, is fastened by a very substantial hinge. On this lid a tablet, *o*, and pencil *p* are attached. The tablet is of such material as can be used with a lead-pencil, and can be made with any material suitable for tablets. The falling lid is used as a handle to draw out the inner box, as is also the ring *w*, Fig. 3, which is fastened to the bottom of the inner box immediately under the hinge of the falling lid. The ring *z*, Fig. 3 and Fig. 2, and *B*, Fig. 1, is attached to the file and safe, to be used in drawing it from the shelf or pigeon-hole. The ring *y*, Figs. 2 and 3, is used for the same purpose. *A*, Fig. 1, is a label.

The mode of using the paper-file and document-safe is to place it with the opening from the operator. Raise the cap-lid with the left hand. With your right hand take hold of the falling lid or the ring near its hinge and draw out the inner box as far as it will come. Then proceed to examine the papers, which are presumed to be suitably labeled near the end in a business-like manner. Having selected your paper, you can register its disposal upon the tablet if it is to be taken from the safe. You close the safe, pressing firmly against the falling lid near the hinge, raising the falling lid and dropping the cap-lid.

What I claim as my invention, and desire to secure by Letters Patent, is—

A combination of two boxes, one within the other and attached, forming a folding box with two lids and a tablet attached, producing a practical file and safe for business papers, as herein described.

W. L. WOODS.
